MICHAL MORAWIECKI, OF PITTSBURGH, PENNSYLVANIA.

BOTTLE CLOSURE OR STOPPER.

1,037,792.

Specification of Letters Patent.

Patented Sept. 3, 1912.

Application filed March 14, 1912. Serial No. 683,783.

To all whom it may concern:

Be it known that I, MICHAL MORAWIECKI, a subject of the Emperor of Austria-Hungary, residing at Pittsburgh, in the county of Allegheny and State of Pennsylvania, have invented certain new and useful Improvements in Bottle Closures or Stoppers, of which the following is a specification, reference being had therein to the accompanying drawing.

This invention relates to a bottle closure or stopper, and the objects of my invention are, first, to provide a closure or stopper that can be easily and quickly placed in the neck of a bottle to seal the same; second, to furnish a closure or stopper with a novel locking device that prevents its removal except by an authorized person equipped with a key; third, to provide a closure or stopper that insures a nonleakable condition, and fourth, to accomplish the above results by a mechanical construction that is simple, durable and highly efficient for the purposes for which it is intended.

The above, and other objects, are attained by the novel construction, combination and arrangement of parts to be hereinafter specifically described and then claimed.

Reference will now be had to the drawing wherein—

Figure 1 is a vertical sectional view of a portion of a bottle provided with the closure or stopper. Fig. 2 is a vertical sectional view of a detached closure or stopper. Fig. 3 is a plan of the same. Fig. 4 is a horizontal sectional view taken on the line X—X, of Fig. 2. Fig. 5 is a similar view taken on the line W—W, of Fig. 2, and Fig. 6 is a side elevation of a key or wrench partly broken away and partly in section.

A closure or stopper in accordance with this invention comprises a tuberous or knob-shaped body 1, having the lower end thereof reduced, as at 2, and the upper end thereof provided with a cylindrical socket 3. The body 1 has a central longitudinal bore 4, rectangular in cross-section, and extends from the lower end of the body to the socket 3. In the lower end of the bore 4 there is mounted a rectangular bushing 5 having a rectangular opening 6 formed therein.

Movably mounted in the bushing 5 is the rectangular shank 7 of a pin 8, said pin having the lower end thereof provided with a head 9. The upper end of the shank 7 is screw threaded at 10, said screw extending

through a metallic washer 11 mounted upon the bottom of the socket 3. A nut 12 is screwed upon the screw 10 for a purpose as will presently appear. Arranged upon the pin 8 and resting upon the head 9 are a plurality of superimposed compressible members or gaskets 13, preferably made of rubber, and these members are adapted to be vertically compressed and laterally expanded by rotating the nut 12 to draw the pin 8 toward the upper end of the body 1.

To facilitate the rotating of the nut 12 a key or wrench 14 can be employed, said key having the lower end thereof provided with sockets 15 and 16, the former providing clearance for the upper end of the screw 10 and the latter receiving the nut 12. With the pin 8 in a lowered position, the lower end of the closure or stopper can be easily placed in the neck 17 of a bottle 18, with the angular shoulder 19 of the body 1 resting upon the upper end of the neck 17. By then placing the key or wrench over the nut 12 and rotating the same the pin 8 can be elevated to expand the members 13 and cause said members to frictionally engage the inner walls of the neck 17 and provide a nonleakable connection between the closure and the bottle neck. As the socket 3 is just of sufficient diameter to accommodate the key or wrench 17, the fingers cannot be inserted in the socket to rotate the nut, consequently the closure or stopper cannot be removed except by the use of the key or some other instrument by which the nut 12 can be gripped.

What I claim is—

A bottle stopper comprising a body having the lower end reduced and adapted to extend into the neck of a bottle, the enlarged portion of said body seated upon the top edge of the neck of the bottle, said body provided with a longitudinal bore terminating at its upper end in a socket at the top of said body, an aperture disk mounted upon the bottom of the socket and constituting an abutment, a bushing provided with a rectangular opening mounted in said bore at the lower end thereof, a pin having a rectangular lower portion extending through said opening and carrying a head at its lower end, the upper portion of said pin being threaded and extending through said disk, resilient gripping members mounted upon said pin and supported at said head and adapted to engage the lower

end of said body and adapted to grip the inner face of the neck of a bottle, and a key operated nut mounted upon the threaded portion of the pin for shifting the latter to 5 elevate the lower said member and engaging said disk for maintaining the pin in an adjustable position.

In testimony whereof I affix my signature in the presence of two witnesses.

MICHAL MORAWIECKI.
